UNITED STATES PATENT OFFICE

THOMAS G. HITT, OF SEATTLE, WASHINGTON

FIRECRACKER COMBINATION

Application filed October 23, 1929. Serial No. 401,689.

This invention relates to pyrotechnics, and more particularly to imitation giant tubular firecrackers, with a plurality of smaller firecrackers of special construction and arrangement, held within the tube.

One object of the invention is to provide a structure which will furnish a series of detonations, and brilliant flashes of various colors, by the exploding of several firecrackers one after the other, but all packed together in a tube formed to represent a giant firecracker.

Another object is to provide an imitation giant firecracker, with a plurality of smaller firecrackers packed together in the tube, the fuses of all the firecrackers ignited at the same time by the same match, but each to explode separately, in sequence one after the other, the first one to provide a loud detonation and to burst the tube retainer, and the others to explode following, and to display various colored flashes as well as separate detonations.

With these and other objects as will further appear in the specification following, I have illustrated my invention by the accompanying drawing, of which:

Figure 1 represents a front elevation of the device, with parts broken away,

Figure 2 represents a plan in section taken on a line 2—2 of Figure 1,

Figure 3 represents a sectional elevation with parts broken away and taken on lines 3—3 of Figure 2, and

Figure 4 represents a sectional elevation with parts broken away, and taken on lines 4—4 of Figure 2.

Like numerals on the different views and figures represent like parts.

Numerals 5 represents the side walls of a tubular container, preferably formed of pasteboard for holding its shape, and yet to be readily broken into small fragments by an explosion within the same. 6 is a bottom cap, and 7 a top cap, the caps are ordinarily held in position on the tube by friction, and the structure resembling a giant firecracker, and preferably so colored. 8, 9, 10 and 11 are smaller tubes for firecrackers packed within the container and each enclosing a determined

charge of explosive of suitable composition for explosions and various colors.

While I show the tubes of equal length for illustration in my drawings, yet the same may be varied to produce differences in the detonations, and to provide differences in the display of the flashes of the explosions.

In tube 8 I preferably place a bag filled with an explosive of sufficient power to shatter the outer tubular container, with a fuse 8' extending from the explosive matter in a bag 12, and out through an opening in the cap or cover 7 to any desired length, for ignition by a match in the usual way.

The bag is preferably arranged and filled as specified in my Letters Patent 1,253,596, and the same arrangement may be carried out so far as practicable in the loading plans of the other tubes, but for the purposes of the illustration herein they may be best shown as 70 loaded with their several charges of explosive packed in their respective tubes and held in place by suitable wads as 13 of any suitable material.

The position of the explosive in tube 8 and 75 the length of the fuse 8' are so arranged that the explosive in the bag 12 will be first fired, and the container thereby shattered.

In tube 9 is preferably packed explosive material which will produce a suitable detonation and provide two distinct colors, shown as 14 and 15. In tube 10 is preferably packed explosive material which will produce a suitable detonation and three distinct colors, shown as 16, 17 and 17', and in tube 11 is 85 preferably packed explosive material which will not only provide a loud detonation, but will display all the colors of the rainbow, shown as 18, 19, 20, 21, 22, 23 and 24. These or other colors may be produced by chemicals suitable for providing the colors separated or blended to substantially produce the effects desired.

The charges in the firecracker tubes are fired by suitable fuses 26, 27 and 28 extending therefrom out through a central opening in the cap 7, and all wrapped together by a thin cover 29, to form the appearance of one large fuse from a giant firecracker. The fuses from all of the firecrackers are ignited 100

at the same instant but the time of the explosions of the several charges in the different tubes is regulated by the positions of the charges in tubes 9 and 10 so that 9 will be discharged with its two colors following the bursting of the first tube 8, and next will be exploded tube 10 with its three colors, all followed by the final explosion of the tube 11, with its seven or other varied colors.

10. In the drawings for illustration, the charges in tube 11 extend the length of the tube, but when in practice the charges are so packed, I provide the tube with a slower fuse, so that its contents will not be consumed and the fire reach the charges in the tube 11 till after the other tubes have exploded, or the several ingredients in tube 11 may be reduced in quantity to require a smaller space, and so be arranged with longer fuse to prolong the time for the explosion as desired.

20. In order to simplify the drawings I have shown but a single fuse for each of the firecrackers, but in practice I prefer to use a plurality of fuses for each tube to guard against failure of igniting the charges, as shown in Letters Patent to me No. 1,600,879.

30. In use the combined ends of the tubes, appearing as one large fuse from the imitation giant cracker, are ignited, and the device thrown upon the ground, or projected into the air by any suitable means, and the several charges will be exploded as they are reached by the burning of their respective fuses. The sequence of the bursting of the container with the accompanying detonation, and the following detonations and variety of colors, furnish a brilliant pyrotechnic display either by day or night, and the weight of the combined firecrackers enclosed in the large container tube, enables the operator to project the device much higher in the air than if the firecrackers were used separately.

40. Having described my invention, I claim as novel for Letters Patent:

45. 1. An imitation giant firecracker, with a container tube, caps on the ends of the tube, a plurality of firecrackers packed into the tube, fuses extending from the firecrackers through the top cap on the tube and held together with a wrapper to be ignited together, the charges in the firecrackers positioned with relation to their fuses so that they will be fired successively.

55. 2. An imitation firecracker with an outer casing and a plurality of firecrackers held together in the casing, fuses from the firecrackers extending from the casing and held together for firing simultaneously, the charge in one firecracker arranged to be first exploded to burst the container, and the charges in the other firecrackers provided with material for various different colors with means for firing the other firecrackers successively in sequence, following the bursting of the container.

3. In combination, a pyrotechnic structure, with a container tube in imitation of a giant firecracker, a plurality of firecrackers held in the container with the fuses from the firecrackers wrapped together and extending from the container to resemble one large fuse for a giant firecracker and to provide for the ignition of all the fuses simultaneously, explosive charges in the firecrackers for causing detonations and flashes of various colors, the charge in one firecracker arranged to be first exploded and of sufficient power to shatter the container, the remaining firecrackers arranged to explode successively and the number of colors from the firecrackers provided by suitable material for increase as they explode, one after the other in sequence.

In testimony whereof I affix my signature.

THOMAS G. HITT.
